UNITED STATES PATENT OFFICE.

JOSEPH A. SEYMOUR, OF FABYAN, NEW HAMPSHIRE.

KNIFE-SHARPENER.

1,027,005.

Specification of Letters Patent. Patented May 21, 1912.

Application filed May 4, 1911. Serial No. 624,987.

To all whom it may concern:

Be it known that I, JOSEPH A. SEYMOUR, a citizen of the United States, residing at Fabyan, in the county of Coos, State of 5 New Hampshire, have invented certain new and useful Improvements in Knife-Sharpener; and I do hereby declare the following to be a full, clear, and exact description of the invention, such as will enable others 10 skilled in the art to which it appertains to make and use the same.

My invention relates to new and useful improvements in sharpening devices, and more especially to that type of machine 15 adapted to sharpen knives and the object of my invention is to improve the construction and increase the efficiency of sharpeners of the above described type.

A further object of my invention is to 20 provide a machine adapted for sharpening both sides of the knife edge at once.

A further object of my invention is to provide means whereby the bevel of both 25 sides of the knife edge will be the same. And a still further object of my invention is to provide a machine for sharpening knives in which a long or short tapered edge may be obtained as desired.

With these and other objects in view my 30 invention will be more fully described, illustrated in the drawings which show a preferred embodiment of my device and then specifically pointed out in the claims which are attached to and form a part of this 35 application.

In the accompanying drawings, Figure 1 is a side elevation partially in section of my improved sharpener, Fig. 2 is a top plan view thereof, Fig. 3 is a front elevation, 40 Fig. 4 is a section through the line 4—4 of Fig. 3, Fig. 5 is a top plan view of the grinding disks showing the manner in which the blade to be ground is positioned.

Referring more specifically to the drawings in which similar reference numerals 45 designate corresponding parts throughout, 1 designates in general the frame of the machine and as shown this frame is provided with a downwardly extending arm 2 by 50 means of which it is adapted to be clamped upon any suitable support the wing bolt 3 serving to secure it in position. As the particular form of frame and clamping mechanism forms no part of my invention no 55 further description of the same is necessary. Journaled in suitable bearings formed in

this frame is a shaft 4 one end of which extends beyond the frame and is provided with any suitable form of power applying means, here shown for convenience as a hand crank 5. Keyed upon this shaft is a spur gear 6 which meshes with a second spur gear 7, said latter spur gear being in turn keyed upon a second shaft 8 also journaled in the frame 1. This shaft 8 is also provided with a second spur gear 9 which meshes with a spur gear 10 which is keyed near one end of the main shaft 11 of the machine, said shaft 11 being also journaled in the frame. This main shaft 11 is provided intermediate 70 its length with two spaced apart grinding disks 12 and 13, the opposing faces of which are beveled as at 14. Secured to the frame 1 and surrounding these grinding disks is a knife holding member which as a whole is designated by the numeral 15. As will be seen by referring to the drawings this knife supporting member consists primarily of a base member 16 and a pair of U-shaped jaw members 17 and 18. This base member is 75 pivotally secured to the frame by a bolt or other preferred means 19 at a point directly below the shaft 11 and intermediate between the grinding disks 12 and 13. The end portions of this base member are bent 80 upwardly as at 20 and 21 and secured to each of said end portions adjacent the terminals thereof is a U-shaped member 22 the side members of which are provided with perforations 23. The side portions of said 85 U-shaped member are further extended upwardly and outwardly to form diverging arms 24 and 25 the end portions of which are perforated as at 26 and mounted in these latter perforations is a shaft 27 upon which 90 is rotatably journaled a roller 28, said roller being preferably formed of some soft metal such as lead. These arms 24 and 25 are so proportioned that the upper faces of the rollers 28 are slightly above the level of the 95 main shaft 11.

The jaw members 17 and 18 previously mentioned, have their lower ends pivotally secured to the end portions 20 and 21 of the base as shown at 29, and as shown these jaw 100 members together with the base member completely surround the periphery of the grinding disks, said jaws being so positioned that their inner edge portions bear against each other, said portions being cut away as 110 at 30 to adapt the jaws to fit around the U-shaped members 22. Secured to the up-

per or right portion of each of said jaws is a vertically extending plate 31, the upper portions of which are bent outwardly as at 32. Mounted in the perforations 23 of each 5 of said U-shaped members is a shaft 33 and the lower portions of each of said U-shaped jaw members are provided with outwardly extending bracket members 34, the end portions of which are provided with apertures 10 somewhat greater in diameter than the diameter of the shafts 33 which shafts extend therethrough. Each end of each of the shafts 33 is provided with an annular flange or collar 35 and surrounding the shafts 33 15 and bearing between these flanges and the bracket members 34 are the helical compression springs 36, the function of which is to maintain the jaws in their normal closed position. By this means the inner edges of 20 the jaws 17 and 18 normally bear against each other as also do the inner faces of the plates 31, but it will be seen that said jaws and plates may be swung away from each other against the action of the springs 36.

25 As previously described the base member 16 is pivotally mounted upon the frame and as a tensional device for preventing unwished for swinging of the same I have provided the member 37, which as shown is substantially U-shaped in section and which is positioned transversely across the base of the knife holder with its ends extending beyond the sides thereof and secured to the frame by means of bolts 38. Surrounding 30 these bolts and bearing between the heads thereof and the base portion of the member 37 are the compressed helical springs 39. By this means the base member 16 is frictionally engaged between the supporting 35 frame and the cross member 37 and it will be seen that a slight amount of force will be required to swing said base together with its knife holding jaws.

In operation the blade of the knife to 40 be sharpened is inserted between the plates 30 and then forced downwardly between the jaws until its edge rests upon the lead rollers 28, the jaws in the meantime due to the tension of the springs 36 maintaining the 45 knife blade in vertical position. The entire knife holding frame is then swung upon its supporting frame, by means of pressure applied to the handle of the knife, until one side of the knife edge bears against the rear 50 portion of the disk 12 and the other side of the knife edge bears against the forward portion of the disk 13. The disks are then 55 revolved by means of the hand crank and gear mechanism previously described, the knife in the meantime being drawn back and forth between the jaws to sharpen it 60 throughout its length. After the action has been continued for a sufficient length of time the knife holding frame is swung in the opposite direction until the knife blade rests

against the rear portion of the disk 13 and the forward portion of the disk 12 when the grinding operation is repeated. By this means both sides of the knife blade are ground throughout their length, and as the 70 bevel of each of the disks is the same both sides of the blade will be equally tapered. The lead rollers prevent the edges of the blade from striking against the shaft 11 and becoming dull.

If an edge with a sharp taper is desired the knife blade is positioned between the jaws at a distance above the rollers instead of resting directly upon them as previously described, the taper of the blade depending entirely upon the portion of the disks engaged by the blade.

The above described device is simple and economical of construction, easy in operation and sharpens the blade uniformly throughout its length, beveling the same equally upon each side. As will be readily seen there are absolutely no adjustments required other than that of positioning the blade at various heights above the rollers according to the bevel desired.

It will be understood that the grinding disks may be of any preferred type of material, such as emery or carborundum, and the frame structure and driving mechanism 95 may be modified in any manner without in the slightest degree departing from the spirit of my invention.

What I claim is:—

1. In a machine for sharpening knives, 100 comprising a frame, a shaft rotatably mounted in said frame, spaced apart grinding disks carried by said shaft, a knife holding member mounted on said frame, said member being pivoted to swing in a horizontal plane, and means for rotating said shaft.

2. A machine for sharpening knives, comprising a frame, a shaft rotatably mounted on said frame, grinding disks carried by said shaft, a knife holding member swingingly mounted on said frame, spring pressed means for normally holding said member against swinging, and means for rotating said shaft.

3. A machine for sharpening knives, comprising a frame, a shaft rotatably mounted on said frame, spaced apart grinding disks carried by said shaft, a knife holding member swingingly mounted on said frame, said member comprising a base portion, jaw 115 members pivotally mounted upon said base portion with their inner edges bearing against each other and spring controlled means for normally holding said jaws in engagement with each other, and means for 120 rotating said shaft.

4. A machine for sharpening knives, comprising a frame, a shaft rotatably mounted on said frame, spaced apart grinding disks carried by said shaft, means for rotating 130

said shaft, a knife holding member swingingly mounted on said frame, said member comprising a base portion having upwardly extending side members, jaw members pivotally mounted upon said base portion with their inner edges bearing against each other, U-shaped members secured to said side members and between the jaw members, said U-shaped members being provided with upwardly directed diverging arms, rollers carried by said arms against which the edge of the knife is adapted to bear, and means co-acting between said U-shaped members and jaws for holding the jaws in engagement with each other.

5 10 15 20 25

5. A machine for sharpening knives, com-

prising a frame, a shaft rotatably mounted on said frame, means for rotating said shaft, spaced grinding disks carried by said shaft and a knife holding member, said member comprising a base portion pivoted to the frame and beneath the grinding disks and adapted to swing in a plane parallel to the base of the frame, and knife holding jaws carried by said base portion.

In testimony whereof, I affix my signature, in presence of two witnesses.

JOSEPH A. SEYMOUR.
